(57) **CLAIM**

I claim the ornamental design for a light emitting diode, as shown and described.

DESCRIPTION

FIG. 1 is a top plan view of a light emitting diode showing my new design;

FIG. 2 is a left side elevation view thereof;

FIG. 3 is a front elevation view thereof;

FIG. 4 is a right side elevation view thereof;

FIG. 5 is a bottom plan view thereof;

FIG. 6 is a rear elevation view thereof; and,

FIG. 7 is a perspective view thereof.
